UNITED STATES PATENT OFFICE.

WILLIAM H. CAHALL, OF RACINE, WISCONSIN, ASSIGNOR, BY MESNE ASSIGNMENTS,
TO ADVANCE-RUMELY COMPANY, OF LAPORTE, INDIANA, A CORPORATION OF
INDIANA.

TRACTION-ENGINE.

1,189,425.

Specification of Letters Patent. Patented July 4, 1916.

Application filed January 18, 1915. Serial No. 2,801.

To all whom it may concern:

Be it known that I, WILLIAM H. CAHALL, a citizen of the United States, residing at Racine, in the county of Racine and State of Wisconsin, have invented a certain new and useful Improvement in Traction-Engines, of which the following is a specification.

My invention relates to improvements in traction engines and has for one object to provide means for suspending the traction engine and means for mounting upon it the driving shaft in such manner that the suspension and the driving shaft will be free 10 from and unaffected by changes in the size of the engine boiler.

Other objects of my invention will appear from time to time in the specification.

My invention, therefore, is illustrated 20 more or less diagrammatically in one form in the accompanying drawings, wherein—

Figure 1 is a rear elevation; Fig. 2 is a part section with parts omitted and parts broken away showing the axle and drive 25 shaft; Fig. 3 is a side elevation with parts in section and parts omitted showing the side of the boiler and the wing plate projecting therefrom; Fig. 4 is a detail section on an enlarged scale showing the means for adjusting the bull shaft; Fig. 5 is a section on the line 5—5 of Fig. 4.

Like parts are indicated by like letters throughout the several figures.

A is the fire box of a traction engine boiler. 35 A¹, A¹ are wing plates rigidly attached to the boiler projecting backwardly therefrom on either side. They are bent over at the top to attach to the curved top of the boiler as at A².

40 A³ is any suitable type of traction engine mounted on the boiler. It drives a fly wheel A⁴.

A⁵ is a pinion rotating with the fly wheel in mesh with the differential gear A⁶.

45 A¹⁰ is a differential housing within the gear A⁶ and containing a differential diagrammatically shown.

A⁷ is a bull shaft. It carries at one end the bull pinion A¹⁸ rotatably mounted thereon, at the other end the bull pinion A⁸, rigidly mounted thereon. These are in mesh with the bull gears A⁹, A⁹ on the driving and supporting wheels A¹⁰ which wheels are mounted on the axle A¹¹ one of the wheels 50 being keyed to the axle the other free to ro-

tate on it in the usual manner. The wing plates A¹ are apertured adjacent their upper and lower edges as at B, B¹.

B² is a sleeve keyed on the shaft A⁷ adjacent the bull pinion A⁸. The pinion A⁸ and the sleeve B² are, of course, connected up to opposed sides of the differential in any suitable manner not here illustrated as it forms no part of my invention.

60 B³ is a cannon bearing extending through the two wing plates and enlarged at either end to contain bearing sleeves B⁴.

B⁵, B⁶ are oil buckets from which the bearings may be lubricated through the passages B⁷.

70 B⁸, B⁹ are slotted arms projecting outwardly from the cannon bearing B³ one on either side of the lug B⁹. The lug B⁹ is rigidly mounted on the boiler and contains a pin B¹⁰ passing through the slotted portion of the arms B⁸, B⁹ to prevent rotation of the cannon bearing B³. The location of the means for preventing rotation of the cannon bearing at the center of the boiler prevents longitudinal movement of the cannon bearing without interfering with the relative expansion and contraction of the cannon bearing and the boiler.

75 C is a substantially semicircular enlargement on the lower side of the aperture B to permit passage of the arms B⁸ when the cannon bearing is placed in position in the wing plates.

80 C¹ is a saddle located in the aperture C and grooved at C² to engage the wing plates A¹ and to be held in position thereon.

85 C⁵ is an engagement surface on the lower side of the cannon bearing B³ to engage the wedge C⁶ which slides upon the upper flat surfaces of the saddle C¹ and may be forced into position by the nut C⁷ on the bolt C⁸ to hold the cannon bearing snugly in position and prevent undue vibration and without interfering with the cannon bearing in sliding through the wing plate A¹.

90 D is a cannon bearing having a semi-cylindrical lining of any suitable material D¹ resting upon the axle A¹¹ in such manner that the lower position of the cannon bearing sleeve is open and free below the axle as at D⁴.

95 D² is a grease cup communicating by means of passages D³ with the bearing surface.

100 D⁵ is a bracket projecting from the boiler.

It is located between the two arms D⁷, D⁷ on the cannon bearing. These arms D⁷, D⁷ are slotted at D⁸ to slidably engage the pin D⁸ on the bracket D⁵ and thus prevent rotation of the cannon bearing without interfering with its freedom to expand or contract with respect to the boiler.

E is a substantially semi-circular aperture projecting downwardly from the bottom of the opening B¹ in the wing plate A¹ to permit entrance of the arms D⁷, D⁷ when the cannon bearing is brought into position.

E' is a flanged eccentric ring held adjustable within the aperture B¹ by means of bolts E². This ring surrounds the cannon bearing D which bearing is free to slide within the ring. The rotary movement of this ring provides a large range of adjustment of the position of the cannon bearing D with respect to the wing plates and thus permits of accurately positioning the shaft A¹¹ with respect to the shaft A⁷ to give the proper distance between the gear centers and to compensate for wear and the like since by withdrawing the bolts E² moving the eccentric ring through a slight distance it is obvious that a large number of adjustments may be obtained.

It will be evident that while I have shown in my drawings an operative device, still many changes might be made both in size, shape and arrangement of parts without departing from the spirit of my invention, and I wish, therefore, that my drawings be regarded as in a sense diagrammatic.

The use and operation of my invention are as follows:—The wing plates are riveted to the boiler. The same is true of the two lugs adjacent the upper and lower extremities of the wing plates. The lower cannon bearing is inserted through the hole in one of the wing plates and carried over until it passes through the other with the arms on the cannon bearing mounted on either side of the lug of the boiler. The pin is then passed through the lug of the boiler and the slots of the arm and the eccentric rings inserted into the openings in the wing plates and surrounding the cannon bearing so that the cannon bearing is mounted slidably in position in the wing plates and held against rotation therein. The two-part axle is then inserted into the cannon bearing and the wheels are mounted thereon. Jacks or other supporting means which have heretofore supported the boiler will be released and the boiler will be allowed to settle so that the weight thereof is carried by the cannon bearing which is supported by the semicircular Babbitt member on the shaft. The upper cannon bearing is then put into position in the same manner so that the two arms thereon are one on either side of the lug on the boiler and the pin is then put in place to prevent rotation. The saddle is then put

into the two semicircular extensions on the openings and the wedges turned up so as to hold the cannon bearing in position without locking it. The bull shaft is then put into place with the bull gears subsequently positioned thereon so that the bull pinions are in mesh with the bull gears on the wheels. The eccentric rings surrounding the lower cannon bearing are then rotated until the distance between the shafts centers is correct and then the eccentric rings are bolted in position. The machine is then ready for the road at least so far as the purpose of my invention is concerned. The bearings have been lined up and the bearings are free to move with respect to the boiler from the anchor point at the center so that the differential expansion and contraction of the boiler and the bearing will not be harmful and will not affect the boiler in any way.

I claim:—

1. The combination of a steam traction engine, of a number of parallel plates apertured, projecting rearwardly from the boiler, a bearing sleeve smaller than said aperture, 90 an arm projecting outwardly from said sleeve, said aperture being large enough to permit passage of the sleeve with the arm, means for holding said sleeve removable in fixed position in said aperture. 95

2. The combination of a steam traction engine with a number of parallel plates apertured, projecting rearwardly from the boiler, a bearing sleeve smaller than said aperture, an arm projecting outwardly from said sleeve, said aperture being large enough to permit passage of the sleeve with the arm, means for holding said sleeve removable in fixed position in said aperture, said means comprising a removable collar interposed between the sleeve and the wall of the aperture. 100 105

3. The combination of a steam traction engine with a number of parallel plates apertured, projecting rearwardly from the boiler, a bearing sleeve smaller than said aperture, an arm projecting outwardly from said sleeve, said aperture being large enough to permit passage of the sleeve with the arm, means for holding said sleeve removable in fixed position in said aperture, a bracket on the boiler and a pin therein in 110 115 slideable engagement with the arm to hold the sleeve and arm against rotation.

4. The combination of a steam traction engine with a number of parallel plates apertured, projecting rearwardly from the boiler, a bearing sleeve smaller than said aperture, an arm projecting outwardly from said sleeve, said aperture being large enough to permit passage of the sleeve with the arm, means for holding said sleeve removable in fixed position in said aperture, said means comprising a removable collar interposed between the sleeve and the wall of the 120 125 130

- aperture, a bracket on the boiler and a pin therein in slidable engagement with the arm to hold the sleeve and arm against rotation.
5. A support for a shaft, comprising a flat apertured plate, a sleeve therein smaller than the aperture and means interposed between the wall of the aperture and the sleeve and removably held therein, for holding the sleeve in fixed position in the aperture.
- 10 6. A support for a shaft comprising a flat apertured plate, a sleeve therein smaller than the aperture and means interposed between the wall of the aperture and the sleeve and removably held therein for holding the sleeve in fixed position to the aperture, said means comprising a saddle block and wedge and means for thrusting said wedge against said saddle block to clamp the sleeve in position.
- 15 7. The combination with a steam traction engine of a pair of parallel wing plates projecting rearwardly from the fire box, said plates being apertured, an axle bearing sleeve loosely mounted in said aperture, means on the sleeve and in engagement with the firebox to prevent rotation of the sleeve, of filler collars interposed between said sleeves and the said walls of the apertures in the wing plates.
- 20 8. In a traction engine, a pair of circularly apertured wing plates, said apertures being downwardly enlarged, filling collars removably mounted within said apertures, a bearing sleeve contained within and supported by said collars and means on the sleeve in engagement with means on the frame for preventing relative rotation of the sleeve and frame.
- 25 9. In a traction engine a pair of relatively flat parallel apertured plates projecting from the main frame, removable collars contained within said apertures, a bearing sleeve removably held within said collars and a shaft rotatable in said sleeve and removable means for preventing rotation of the sleeve.
- 30 10. A transmission for traction engines and the like comprising a pair of substantially parallel cannon bearings, an axle in one and a bull shaft in the other, means for anchoring said cannon bearings to the boiler at the center line and means for slidably connecting the boiler and the cannon bearings adjacent the ends of the bearings.
- 35 11. The combination with a traction engine boiler and wing plates projecting therefrom of a cannon bearing slidably mounted in said wing plates and means for holding said cannon bearing against rotation and against longitudinal movement independent of said wing plates.
- 40 12. The combination with a traction en-
- gine boiler and wing plates projecting therefrom of a cannon bearing slidably mounted in said wing plates and means for holding it against rotation.
- 45 13. The combination with a traction engine boiler and wing plates projecting therefrom of a cannon bearing slidably mounted in said wing plates and means for holding it against longitudinal movement independent of said wing plates.
- 50 14. The combination with a traction engine boiler and wing plates projecting therefrom of a plurality of cannon bearings movable in said wing plates and means for adjusting the distance between said bearings.
- 55 15. The combination with a traction engine boiler and wing plates projecting therefrom of a plurality of cannon bearings movable in said wing plates and means for adjusting the distance between said bearings, said means comprising an eccentric ring surrounding one of said bearings.
- 60 16. A supporting means for a traction engine comprising a pair of apertured parallel wing plates, a cannon bearing passing through said plates, a supporting ring removably mounted in the aperture in each plate and in slidable and rotatable engagement with the cannon bearing and means for holding said ring in position in the plate.
- 65 17. A supporting means for a traction engine comprising a pair of apertured parallel wing plates, a cannon bearing passing through said plates, a supporting ring removably mounted in the aperture in each plate and in slidable and rotatable engagement with the cannon bearing and means for holding said ring in position in the plate, said apertures being irregular, said cannon bearing being provided with an arm and means movably attached to the traction engine to prevent rotation of the cannon bearing, said rings being adapted to effectively close the irregular portion of said aperture after the arm has been inserted through it.
- 70 18. The combination with a traction engine, a cannon bearing therefor and means for anchoring said bearing to the boiler at the center to prevent rotation and longitudinal movement and a slidable connection between the boiler and the cannon bearing at the end.
- 75 In testimony whereof, I affix my signature in the presence of two witnesses this 9th day of January, 1915.
